UNITED STATES PATENT OFFICE.

SARAH F. HAMMONS, OF CHICAGO, ILLINOIS.

DESIGN FOR A RECORD TABLET, PLATE, FRAME, OR THE LIKE.

53,301.

Specification for Design.

Patented May 13, 1919.

Application filed January 25, 1919. Serial No. 273,160. Term of patent 3½ years.

To all whom it may concern:

Be it known that I, SARAH F. HAMMONS, a citizen of the United States, residing at Chicago, in the county of Cook and State of Illinois, have invented a new, original, and ornamental Design for a Record Tablet, Plate, Frame, or the like, of which the following is a specification, reference being had to the accompanying drawing, forming part thereof.

The figure is a view of a record tablet showing my new design.

I claim:

The ornamental design for a record tablet, plate, frame, or the like, substantially as shown,

SARAH F. HAMMONS.
